Robert H. Aldrich, Parchment, Mich., assignor to Ham-mond Machinery Builders, Inc., Kalamazoo, Mich., a corporation of Michigan

Application September 8, 1958, Serial No. 52,559

Term of patent 14 years

(Cl. D9—2)

Figure 1 is a perspective view of a dust collector unit embodying my new design.

Figure 2 is a side elevational view thereof.

Figure 3 is a top plan view thereof.

The dominant features of said dust collector unit reside in the portions thereof shown in solid lines.

I claim:

The ornamental design for a dust collector unit, as shown and described.
